UNITED STATES PATENT OFFICE.

ELMER J. SHIRLEY, OF EL MODENA, CALIFORNIA.

HAY-PRESS.

SPECIFICATION forming part of Letters Patent No. 634,544, dated October 10, 1899.

Application filed April 4, 1898. Serial No. 676,459. (No model.)

To all whom it may concern:

Be it known that I, ELMER J. SHIRLEY, a citizen of the United States, residing at El Modena, in the county of Orange and State of California, have invented new and useful Improvements in Hay-Balers, of which the following is a specification.

This invention relates to condensers and feeders for hay-balers, and is applicable to any baler.

In the drawings I have illustrated my invention as applied for the double-acting hay-baler described in Letters Patent of the United States No. 593,383, issued to me November 9, 1897, and in which a plunger moves to and fro underneath the feed-opening and operates to force the alternate wads or charges in opposite directions to form duplicate bales.

20 My present invention comprises the combination of a baling-press frame, a plunger playing therein, a lever pivoted to the frame and provided on one arm with a condenser-head to play toward and from the feed-opening, and means operatively connecting the plunger with the lever to move the condenser-head toward and from said opening. Preferably two oppositely-moving condenser-heads are employed, being mounted on levers, respectively, and arranged to play toward and from each other in the condensing-hopper and on opposite sides of the feed-opening, two guides being fastened to the plunger to move therewith and two travelers, one on each 35 of said levers and respectively engaging the said guides to be operated thereby to throw the heads in and out when the plunger is moved to and fro, the said levers being respectively pivoted to the frame on opposite 40 sides thereof and at the lower ends of the levers.

My invention also includes the combination, with one or both of said levers, (preferably with both of said levers,) of a feeder-carrying arm pivoted to the frame, a feeder pivoted to the upper end of said feeder-arm and arranged to play into and out of the feed-opening, a connecting-rod connecting the frame and the feeder eccentric of the pivots of the arm, a feeder-arm-operating lever

pivoted to the frame and slidingly connected with the feeder-arm to slide therealong to operate the same on its pivot, a guide fastened to and moving with one of the condenser-levers, (and in practice each lever is provided with such a guide,) a lever for each guide pivoted to the frame and having one end in engagement with its guide to be operated thereby, and a connecting-rod connecting said lever with said feeder-arm-operating lever, so that when the lever which carries the condenser-head is operated the feeder-arm will be operated.

Various modes of connecting the feeder-arm to be operated with relation to the movements of the condenser-head may be devised without departing from the spirit of my invention, and in the drawings I have shown the means which I regard as most desirable for the purpose, and in this form the guide which is connected with the plunger to move therewith is provided with a bent slot—that is to say, a crooked guideway—having a straight portion in the middle and an oblique portion at each end of the straight portion and a short straight portion at the ends of the slot, and in this slot a traveler runs, the same being fastened to and practically forming one end of the condenser-head lever.

The accompanying drawings illustrate my invention.

Figure 1 is a fragmental side view of a hay-baler embodying my invention. The parts are shown in position with the feeder raised and the condenser-heads thrown out to admit a charge of hay. Dotted lines indicate the position of the parts when the feeder is at its lowest point and the condenser-heads thrown to their inmost position. Fig. 2 is a plan view of the same with the feeder down and the condenser-heads thrown in. Parts are broken away to show working parts that would otherwise be hidden. Fig. 3 is a cross-section on line 3-3, Fig. 2, looking toward the feeder which is shown up. Parts are broken away to expose parts that would otherwise be hidden. Fig. 4 is a fragmental view illustrating the construction of the folder. Fig. 5 is an end view of the folder.

A indicates the baling-frame, provided with

a condenser-hopper B with parallel sides *b b'* extending across the frame at the sides of the feed-opening *a*.

5 *C C'* indicate two levers pivoted to the frame on opposite sides thereof, respectively, and respectively provided at their upper ends with condenser-heads *c c'*, arranged to play toward and from each other in the hopper on opposite sides of the feed-opening to condense the charges of hay which are placed in the hopper. Preferably the path of the condenser-heads will extend to a point a little beyond the sides of the feed-opening *a*.

10 *D* indicates the plunger, having the plunger-head *d*, which works in the baling-chamber in the ordinary manner.

15 *E E'* indicate two guides fastened to the plunger and moving therewith.

20 *c² c³* indicate two travelers, one on each of said levers *C C'* and respectively engaging the guides *E E'* to be operated thereby to operate the said levers to throw the heads in and out when the plunger is moved to and fro. Preferably the levers *C C'* are pivoted to the frame 25 at the lower ends of said levers by pivots *c⁴*, the upper arm of the lever being considerably longer than the lower arm, so that comparatively a small lateral movement of the travelers will produce a considerable movement of the condenser-heads.

30 *e e'* indicate slots in the guides *E E'*, respectively, and the travelers play in said slots. Each guide-slot is crooked, so that it has a straight middle portion 1 parallel with the 35 path of the plunger and at the ends of said parallel portion oblique portions 2 2', each about equal in length to the length of the straight portion 1 and at the ends of the said oblique portions of the slot short portions 3 3'

40 in a line parallel with the middle portion 1 of the slot. When the plunger moves, the guides are carried therewith, and at the middle portion of its movement when the plunger-head is passing the feed-opening there 45 will not be any movement of the condenser-heads; but when the plunger-head has fully or nearly passed the feed-opening the oblique walls of the slot will engage the traveler, thus throwing it outward and throwing the condenser-heads inward to the desired position 50 to condense the charge of hay or other material to be baled, and at the final movement of the plunger-head the condenser-heads will remain stationary for a short portion of the 55 beginning of the return stroke, and then when the oblique walls of the slots again engage the traveler the condenser-heads will be thrown out, thus to allow a charge of hay or other material to be baled to be placed in the 60 hopper, and the heads will remain out until the plunger-head has again wholly or partially passed the feed-opening, and then the condenser-heads will again be thrown in.

65 *F* indicates a feeder-carrying arm pivoted to the frame by a pivot *f*.

G indicates the feeder, pivoted to the feeder-

arm *F* by a pivot *g* and arranged to play into and out of the feed-opening.

70 *H* indicates a connecting-rod pivoted to the frame and the feeder eccentric to the pivots of the arm, preferably being pivoted to the frame and to said feeder, respectively, above the pivots which carry the feeder-arm *F* and the feeder. The feeder-arm is preferably slotted intermediate its pivotal points, and the lever *H'*, which operates the same is provided with a traveler *h'*, which slides in the slot *f'* and by which the lever *H'* is slidably connected with the feeder-arm *F*. The slot is in the arc described by the traveler *h'* when the lever 80 *H'* is operated. The feeder-carrying-arm-operating lever *H'* is pivoted to the frame *A* by a pivot *h* and slidably connected with the feeder-carrying arm *F* to slide therealong.

85 *I* indicates a lever pivoted to the frame at *i* and having one end in engagement with the guide *J*, which is carried by the lever *C*, and is thereby operatively connected with the plunger to be operated by said plunger. *K* is a connecting-rod connecting said lever with 90 the feeder-arm-operating lever *H'*. The guide *J* is provided with a bent slot *j*, and the lever *I*, which is pivoted to the frame by the pivot *i*, is provided with a traveler *i'*, which runs in said slot. A portion of the slot runs transverse the path of the condenser-head lever *C* and another portion of the slot runs at right angles thereto and practically parallel with the path of the condenser-head lever. The guide *J* is in an arc drawn from the pivot *c⁴* 100 of the condenser-head lever. As the lever *C* swings to and fro the traveler *i'* will be moved to operate its lever to operate the connecting-rod *K* to thereby operate the feeder-arm-operating lever *H'* through a portion only of the 105 movement of the condenser-head. When the traveler turns into the transverse portion *j'* of the slot *j*, the feeder-arm is thereby operated during the latter portion of the inward movement and the first portion of the outward 110 movement of the condenser-head. The slot *j* is arranged so that the feeder-arm will be thrown up clear out of the feed-hopper when the condenser-heads are only partially thrown out, so that the feeder-arm will be out of the 115 way to allow a charge of hay to be fed into the hopper, and it will be again inserted into the feed-hopper and forced down into the feed-chamber before the condenser-heads have fully condensed the wad, the purpose being 120 to carry the hay down in an even wad to extend from top to bottom of the feed-chamber. The feeder-arm pushes down in the uncondensed hay and carries the hay down while the condenser-heads are closing their stroke, 125 so that the final operations of condensing and forcing the wad into the chamber are performed simultaneously and the charge or wad of hay is practically of the same density from top to bottom of the feed-chamber. 130 The feeder-board is preferably forked, as shown, so as to carry the hay down properly.

M indicates a folder comprising a shaft *m*, journaled to the frame A and provided with a crank-arm *m'* and with a folder-blade *N*, fixed to such shaft and extending into the path of the bale charge.

5 O indicates a stop in the path of the crank-arm, and P a spring to yieldingly hold the crank-arm against the stop with the blade in the path of the bale charge. A folder is applied at each end of the feed-chamber, so that when the plunger moves in either direction the folder will properly fold the charge.

The folder is arranged to be readily removed and replaced, and for this purpose the folder-shaft is preferably split with a slit *m''* and the folder-blade *N* is arranged in said slit and with a bent edge *n* to rest on the top of said shaft, and suitable means are provided for holding the blade in the slit. Preferably 15 the blade is provided with two shoulders, a shoulder *n'* at one end of the blade extending beneath the unsplit portion *m'''* of the shaft and a shoulder *n''* at the other end of the blade to fit under a sleeve Q, through which 20 the shaft is inserted, so that the blade is held in the shaft by the shoulders.

In practice the opposite sides of the machine are duplicates, so that both of the levers C C' operate to actuate the feeder-arm and 25 both condenser-heads move at the same time to condense the charge. When the condenser-heads have partly condensed the charge, the feeder-arm is operated, and by 30 the time the condensers have completed their inward movement the feeder-arm has completed its downward movement, as indicated in dotted lines in Fig. 1. Then the feeder is quickly withdrawn and held withdrawn until 35 the charge has been compressed by the plunger and the condenser-heads fully thrown open. Then another charge is placed in the hopper and the operation just described is again 40 repeated.

Now, having described my invention, what 45 I claim as new, and desire to secure by Letters Patent, is—

1. The combination of a baling-frame provided with a condenser-hopper; two levers pivoted to the frame on opposite sides thereof 50 and respectively provided at their upper ends with condenser-heads arranged to play toward and from each other in the hopper on opposite sides of the feed-opening; a plunger; two guides fastened to the plunger; two 55 travelers, one on each of said levers and respectively engaging the guides to be operated thereby to throw the heads in and out when the plunger is moved to and fro; a feeder-carrying arm pivoted to the frame; a feeder pivoted to the upper end of said feeder-carrying arm and arranged to play into and out 60 of the feed-opening; a connecting-rod connecting the frame and the feeder, eccentric of the pivots of the arm; the feeder-carrying 65 arm-operating lever pivoted to the frame and slidingly connected with the feeder-carrying

arm to slide therealong; a guide fastened to one of the condenser-levers; a lever pivoted to the frame and having one end in engagement with said guide to be operated thereby; 70 and a connecting-rod connecting said lever with said feeder-arm-operating lever.

2. The combination of a baling-frame; a plunger playing therein; a lever pivoted to the frame and provided on one arm with a 75 condenser-head to play toward and from the feed-opening; a slotted guide connected with the plunger to move therewith the slot thereof having a straight central portion, a straight portion at each end, and an oblique portion 80 connecting each end portion with the central portion; and a traveler on the lever and extending into the slot to be operated thereby.

3. The combination of a baling-frame; the feeder-carrying arm pivoted to the frame; the 85 feeder pivoted to the upper end of said feeder-carrying arm and arranged to play into and out of the feed-opening; a connecting-rod pivoted to the frame and to the feeder, eccentric the pivot of the arm; the feeder-carrying 90 arm-operating lever pivoted to the frame and slidingly connected with the feeder-carrying arm to slide therealong; a guide operatively connected with the plunger to be operated thereby; a lever pivoted to the frame and 95 having one end in engagement with said guide to be operated thereby; and a connecting-rod connecting said lever with said feeder-arm-operating lever.

4. The combination of a baling-frame; a 100 feeder-carrying arm pivoted to the frame; a feeder pivotally secured to the free end of said arm, said arm being slotted longitudinally between said pivotal points; a lever pivoted to the frame and provided with a 105 traveler arranged to move in the slot of said arm; a plunger working in said frame; and means operatively connecting the plunger with said lever to operate the same.

5. The combination of a baling-frame; a 110 plunger working in the frame; a lever pivoted to the frame and provided with a condenser-head thereon and also provided with a traveler; and a guide connected with the plunger to move therewith and provided with 115 a slot in which the traveler runs, one portion of which slot is at right angles to the other portion.

6. The combination with a baling-frame; of a split shaft journaled to the frame and having a crank-arm at its end; a folder-blade in said split and with a bent edge to rest on said shaft; means for holding the blade in the split; a stop for the arm; and a spring to yieldingly hold the crank-arm against the 120 stop with the blade in the path of the bale charge.

7. The combination with a baling-frame, of a split shaft with crank-arm and the folder-blade inserted in the split and with bent edge 125 resting on the shaft and a shoulder at one end of the blade extending beneath the un-

split portion of the shaft; and means for holding the other end of the blade in the shaft.

8. The combination of a baling-frame; the condenser-head pivoted to the frame; a guide 5 fastened to the plunger and provided with a slot; a lever pivoted to the frame and provided with a traveler arranged in said slot; a feeder-carrying arm; the feeder-carrying-

arm-operating lever pivoted to the frame and operatively connected with the feeder-carrying arm; and a connecting-rod connecting said lever with the traveler-carrying lever.
